UNITED STATES PATENT OFFICE.

WILLIAM C. HAWLEY, OF CHICAGO, ILLINOIS.

TOBACCO-PIPE AND CIGAR-HOLDER.

1,185,661.

Specification of Letters Patent.

Patented June 6, 1916.

Application filed October 11, 1915. Serial No. 55,272.

To all whom it may concern:

Be it known that I, WILLIAM C. HAWLEY, a citizen of the United States, residing at Chicago, in the county of Cook and State of Illinois, have invented certain new and useful Improvements in Tobacco-Pipes and Cigar-Holders, of which the following is a specification.

My invention relates to tobacco pipes, 10 cigar holders and cigarette holders, and has special reference to improvements in the mouth pieces thereof.

Pipes and holders are subjected to by most smokers because of the unpleasant effect of 15 the smoke on the tongue and roof of the mouth. This effect or "biting" is commonly supposed to be caused by the unexplained manner in which tobacco burns in a pipe or holder, as contrasted with the free burning 20 of a cigar; and is often attributed to the quality of the tobacco, particularly to kinds that burn more hotly than others. I conceive that neither explanation is correct; and that, instead of being an unavoidable incident of the smoking of tobacco in pipes 25 and holders, the burning or "biting" effect is due to the improper construction of the bit, stems, or mouth pieces.

To prevent the too rapid burning of the 30 tobacco, the duct leading from the bowl and opening through the mouth piece of a pipe or holder, is made very small, in proportion to the size of the bowl; and it is now clear to me that the objectionable "biting" is 35 caused by the constriction, and consequently velocity, of the smoke in the small duct and the accompanying concentration and direct impingement of the hot smoke upon the tongue or the roof of the mouth. Proceeding 40 on this conception and observation, and with the distinct purpose of lessening and obviating the "biting" effect, I form the stem or mouth piece in such manner that the velocity of the smoke leaving the bowl is 45 reduced before the smoke emerges from the mouth piece and the stream of smoke, instead of being concentrated and emitted at one point, is sub-divided and pleasantly diffused in the mouth.

50 My invention will be readily understood upon reference to the drawings that form a part of this specification, in which I have exhibited my invention in the form that I prefer.

55 In said drawings, Figure 1 illustrates a tobacco pipe provided with a stem, bit, or

mouth piece embodying my invention;—Fig. 2 shows a modified form of the mouth piece in which the smoke duct opens through the top;—Fig. 3 is an enlarged longitudinal section of the pipe stem or piece shown in Fig. 1;—Fig. 4 is a longitudinal section of my invention in the form of a cigar or cigarette holder;—Fig. 5 is a cross section on the line 5—5 of Fig. 3;—Fig. 6 is a cross section 60 on the line 6—6 of Fig. 3;—Fig. 7 is a cross section on the line 7—7 of Fig. 3;—Fig. 8 is an end view of the mouth piece;—Fig. 9 is an end elevation of the stem shown in Fig. 1.

No attempt is made to show more than typical forms of my invention, for it is obvious that any skilful pipe maker can readily apply the invention in many forms; and, to a great variety of pipes and holders.

The tobacco pipe shown in Fig. 1, and the cigar holder in Fig. 4, are of familiar shapes. They differ from others only in the form and arrangement of their smoke ducts. The bowl, A, of the pipe is shown 80 by dotted lines in Fig. 1; and the bowl, B, of the holder clearly appears in full lines in Fig. 4. The smoke ducts of the pipe and the holder are the same, except as they are affected by the differing lengths thereof. 85 Each smoke duct comprises several portions, that have different functions. Thus each smoke duct is composed of a duct proper, C, in direct communication with the bowl;—a preferably triangular duct- 90 enlargement or chamber, D, that receives the smoke from the portion, C;—and, three separate ducts, E, E, E, which lead from said chamber, D, and all of which open through the end, F, of the mouth piece or 95 bit. The ducts, E, may open straight through the end, F, as shown in Fig. 1, or they may open through the top of the bit, as shown in Fig. 2. I prefer the straight ducts of Figs. 1, 3 and 4 to 100 the bent ducts of Fig. 2 because the straight ducts fully serve the purpose, and may be cleaned more easily. The portion, C, of the smoke duct is of the usual size of the corresponding duct in an ordinary pipe stem or cigar holder. Its size determines the "draft"; which is a factor that has been nicely determined in the past, and which I prefer not to disturb or modify.

Because of the constricting or choking effect of the portion, C, of the smoke duct, I term it the "choke" or "choke portion" of 105 110

the mouth piece. When smoke emerges from the choke and enters the portion, D, it expands. Thus its velocity is diminished; and, some of the heat is there dissipated. 5 For these reasons the term "expansion chamber" is appropriate to the portion, D. Obviously the smoke is exhausted from the expansion chamber by way of the several diverging or diffusing ducts, E. It follows 10 that the smoke leaves the ducts, E, at greatly diminished velocity and at quite widely separated points. In this way I effectively dissipate a portion of the heat; reduce the velocity of the smoke entering the mouth; 15 lessen the impact thereof upon the tongue or walls of the mouth; and also widely diffuse the smoke; thereby overcoming and doing away with the ill effects suffered in the use of ordinary pipes or holders. It is 20 best to form this smoke duct by drilling or molding the stem. In either case I prefer to employ drills, or several mold cores, which are straight, as opposed to curved, and may be withdrawn easily. By making 25 the ducts, C, and, E, in this manner the intermediate or expansion chamber, D, is automatically or incidentally produced.

My invention possesses the advantage that all parts of the smoke duct may be cleaned 30 by means of an ordinary pipe cleaner, there being no abrupt bends or curves to interfere.

At first glance it may be supposed that more than three diffusing ducts, E, may be

advantageously provided in the mouth piece, 35 but I observe that most mouth pieces are flat and I find that either two or three diverging ducts in the same horizontal plane best serve the purpose and yet may be formed without materially reducing the 40 strength of the bit at the point where it is apt to be crushed by the teeth of the smoker. The importance of the dividing walls, struts, or partitions, E', between the ducts, E, should be noted in this connection. 45 The expansion chamber, D, (well shown in Fig. 7) does not require such struts because it is beyond the reach of the smoker's teeth.

Having thus described my invention, I claim as new and desire to secure by Letters 50 Patent:

1. The herein described improvement, comprising a smoker's mouth piece having a smoke duct composed of a choke and a plurality of diffusion ducts that converge 55 therein and form an intermediate expansion chamber.

2. The herein described improvement, comprising a smoker's mouth piece containing a smoke duct that is choked adjacent 60 the bowl and which terminates in several branches, each of the same size as the choke, and all opening through the other end of the mouth piece.

In testimony whereof, I have hereunto set 65 my hand this 7th day of October, 1915.

WILLIAM C. HAWLEY.
